United States Patent Office

Des. 186,473
Patented Oct. 27, 1959

186,473

PHOTOGRAPHIC CAMERA

Clare E. Hodgman, Mamaroneck, N.Y., assignor to General Aniline & Film Corporation, New York, N.Y., a corporation of Delaware

Application December 22, 1958, Serial No. 53,853

Term of patent 14 years

(Cl. D61—1)

FIG.1

FIG.3

Fig. 1 is a perspective view of the front and one side of a photographic camera, showing my new design, the opposite side being substantially a mirror image thereof;

Fig. 2 is a rear elevational view thereof; and

Fig. 3 is a front elevational view.

I claim:

The ornamental design for a photographic camera, substantially as shown and described.
